Faye Glass, New York, N. Y.

Application September 3, 1940, Serial No. 94,782

Term of patent 3½ years

To all whom it may concern:

Be it known that I, Faye Glass, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the rear view thereof.

The characteristic feature of my design resides in the combination on the coat-dress disclosed of the specific, angularly disposed, front yoke members forming pockets on the blouse portion, said pockets being tucked and stitched as shown.

I claim:

The ornamental design for a dress, substantially as shown and described.

FAYE GLASS.
